STONE POLISHING MACHINE

William G. Cumming, Barre, Vt., assignor to
 Granite City Tool Company, Barre, Vt., a corporation of Vermont

Application February 18, 1936, Serial No. 64,431

1 Claim. (Cl. 51—126)

This invention relates to stone polishing machines of the type employing polishing wheels which rest on the stone and rotate about vertical axes, the wheels comprising a disk having eccentric scrolls attached to their lower faces and operating upon the stone through the medium of iron shot or other abrasive material.

Objects of the invention are to polish convex, concave or other warped surfaces, to facilitate the manipulation of polishing wheels of the type referred to, to reduce the vibration and tendency of the wheels to chatter, to increase the quality and rate of polishing, to prolong the life of such machines and generally to improved the art of stone polishing.

The present invention comprises a horizontal beam with means for adjustably supporting the beam for endwise movement, one end of the beam carrying means for supporting a polishing wheel for rotation about a vertical axis and the motor for driving the wheel preferably being mounted on the other end of the beam. The beam is supported intermediate its ends for horizontal swinging and for vertical tipping. The preferred means for this purpose comprises a support pivoted about a horizontal axis to a stub shaft extending upwardly into a sleeve containing bearings for the shaft, at least one bearing being arranged to support the shaft in the sleeve. In the preferred embodiment the supporting means is carried by a crane which is adjustably mounted on an upright so that it may be raised and lowered and also swung horizontally.

The invention also comprises means for adjusting the aforesaid beam endwise on its support. This means comprises a part fast to the beam, a part fast to the support and interconnecting means for producing relative movement of the parts toward and from each other. More specifically said means preferably comprises cable wheels mounted on the beam on opposite sides of the support together with a cable extending around the wheels and having its ends attached to the support and means for rotating one of the wheels. The wheel to be actuated is preferably a sprocket wheel and at least that portion of the cable cooperating with that wheel comprising a chain meshing with the sprocket wheel.

Other aspects of the invention will appear from the following description and the accompanying drawing of one concrete embodiment. In the drawing,

Fig. 1 is a front elevation of the machine;

Fig. 2 is a section on line 2—2 of Fig. 1; and Fig. 3 is a section on line 3—3 of Fig. 2.

The particular embodiment of the invention chosen for the purpose of illustration comprises an upright 1 upon which the crane 2 is mounted for vertical movement and also horizontal swinging. Vertical movement of the crane is facilitated by means of two rollers 3 engaging opposite sides of the upright 1 and the crane is maintained in horizontal position by means of a brace 4 connected at its lower end to a sleeve 5 surrounding the upright 1. Two sheaves 6 are mounted on the upper end of the upright by means of a bracket 7 and another sheave 8 is mounted on the upper side of the crane 2. A winding drum 9 is mounted on the crane adjacent the upright and is arranged to be rotated by means of a motor 10 connected to the winding drum through the medium of a worm 11 and worm-wheel 12. A cable 13 extends around the sheaves 6 and 8 and around the drum 9, one end of the cable being connected to the bracket 7 and the other end to the drum 9. Thus when the drum 9 is rotated in one direction the crane is lifted by winding the cable around the drum, and when the drum is rotated in the opposite direction the crane is lowered by unwinding the cable.

Depending from the outer end of the crane 2 is a sleeve 14 containing two anti-friction bearings 15 and 16 for the swivel shaft 17, the upper bearing being arranged to support the shaft. Mounted on the lower end of the swivel shaft 17, by means of a horizontal pivot pin 18, is a support 19 carrying four rollers 20. Mounted upon these rollers is a horizontal beam comprising two channel members 21 having their flanges directed inwardly over and under the rollers 20, the two channels being tied together by straps 22 underneath the channels. Mounted on the upper side of the horizontal beam on opposite sides of the support 19 are a sheave 23 and a sprocket wheel 24. Extending around these two wheels is a cable having its opposite ends connected to the support 19, the portion 25 of the cable cooperating with the sheave 23 comprising steel wire and the portion 26 of the cable cooperating with the sprocket wheel 24 comprising a chain meshing with the teeth of the sprocket wheel. The sprocket wheel 24 is arranged to be rotated by means of a handwheel 27 kinematically interconnected with the sprocket wheel through the medium of a shaft 28 and worm gearing 29.

Mounted on one end of the beam 21 is a gear casing 30 containing bevel gears 31. Extending

downwardly from the gearing 31 through a bearing in the lower side of the casing 30 is a shaft 32 which is connected to the polishing wheel 33 through a flexible coupling 34. Adjacent the 5 casing 30 is an abrasive reservoir 35 having an outlet duct 36 for delivering abrasive through openings in the top of the polishing wheel 33. Mounted on the other end of the beam 21 is a motor 37 which is interconnected with the gearing 31 through the medium of shaft 38 and flexible 10 couplings 39 and 40. By providing a flexible coupling at each end of the shaft 38 vibration of the apparatus is greatly reduced.

The beam 21 carries a bail-like handle 41 for 15 manipulating the wheel 33 over the slab of stone 42 mounted on block 43 within an enclosure 44. The beam also carries, adjacent the handle 41 and the handwheel 27, two electrical control devices 45 and 46 for the motors 10 and 37 respectively.

From the foregoing it will be evident that a single operator standing outside the enclosure 44 adjacent the handle 41 can readily manipulate the entire apparatus from this one location, raising and lowering the beam by means of motor 10 and control 45, starting and stopping the wheel by means of motor 37 and control 46, adjusting the beam lengthwise on the support 19 by means 25 of the handwheel 27 and swinging the beam 21 horizontally by means of the handle 41. Thus the polishing wheel 33 may readily be placed on the slab of stone 42 and then easily manipulated over the upper surface of the slab, the motor 37 tending to counter-balance the parts carried by the other end of the beam. It will also be evident that my improved machine is especially 30 adapted to polish warped surfaces, or flat surfaces which are not level, as well as flat level

surfaces, without any change in the machine in changing from one type of work to another.

It should be understood that the present disclosure is for the purpose of illustration only and that this invention includes all modifications and equivalents which fall within the scope of the 5 appended claim.

I claim:

A stone polishing machine comprising a normally fixed overhead carrier, a substantially vertical sleeve having its upper end fixedly secured to the carrier, a freely rotatable swivel shaft within the sleeve, antifriction bearings for the swivel shaft disposed within the sleeve adjacent the opposite ends of the latter, one at least of 10 said bearings being constructed and arranged to support the weight of the swivel shaft and parts carried by the latter, a support, and a pivotal connection so uniting the support to the lower end of the swivel shaft as to permit the 15 support to tilt about a horizontal axis, a beam structure including a pair of substantially parallel rigidly connected channel members each having its flanges directed inwardly toward the other 20 channel member, two pairs of rollers mounted on the support, said pairs of rollers being disposed between the flanges of the respective channel members, bearing means adjacent to one end of the beam structure for a normally vertical polishing wheel shaft, a polishing wheel on the lower 25 end of the latter shaft, means adjacent to the opposite end of the beam structure for supporting a driving motor, drive connections extending longitudinally of the beam structure from the motor to the polishing wheel shaft, and manually 30 actuated means, reacting between the support and beam structure whereby the latter may be moved longitudinally relative to its support.

WILLIAM G. CUMMING.
